(57) **CLAIM**

The ornamental design for a surgical blade loader, as shown and described.

DESCRIPTION

FIG. 1 is a front perspective view of a surgical blade loader showing our new design in a first position;
FIG. 2 is a rear elevation view thereof;
FIG. 3 is a front elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a front perspective view of the surgical blade loader showing our new design in a second position;
FIG. 9 is a front elevation view thereof;
FIG. 10 is a rear elevation view thereof;
FIG. 11 is a left side elevation view thereof;
FIG. 12 is a right side elevation view thereof;
FIG. 13 is a bottom plan view thereof; and,
FIG. 14 is a top plan view thereof.

The dot-dash broken lines and evenly spaced broken lines immediately adjacent to the shaded areas depict the bounds of the claimed design while all other broken lines are directed to environment and are for illustrative purposes only; the broken lines form no part of the claimed design. The "Bard-Parker" lettering and icon forming part of the claimed design is a registered trademark of ASPEN SURGICAL PRODUCTS, INC.
